UNITED STATES PATENT OFFICE.

EUGENE B. TANNER, OF ATTICA, OHIO.

IMPROVEMENT IN HAY-CARRIERS.

Specification forming part of Letters Patent No. 138,955, dated May 13, 1873; application filed April 12, 1873.

To all whom it may concern:

Be it known that I, EUGENE B. TANNER, of Attica, in the county of Seneca and State of Ohio, have invented a new and Improved Hay-Carrier, of which the following is a specification:

In the accompanying drawing, Figure 1 represents a side view of my improved hay-carrying apparatus as attached to the rafters of a barn. Fig. 2 is a vertical transverse section of the roof on the line *c c*, Fig. 1, showing hoisting arrangement of the same; and Fig. 3 is a vertical longitudinal section of the tackle-block, with weighted lever for conveying the load.

Similar letters of reference indicate corresponding parts.

The object of my invention is to furnish to farmers and others a simple, effective, and economical apparatus for hoisting, carrying, and depositing rapidly hay-bales to the desired place in the barn, saving time and labor thereby. My invention consists of lever and guide-pieces, in connection with a pulley having a weighted catch-lever for suspending the load till ready to drop the same. Suitable guide-strings and pulleys facilitate the rapid action of the conveying apparatus.

In the drawing, *A* represents the rafters of a barn or other building, to which are attached, by suitable iron brace-bars or supports *a*, the fulcrum or guide-bar *B*, of wood or other material, and of such length as to convey the load from the starting-place to the point of deposit. Guide-bar *B* is placed in the direction of the longitudinal axis of the barn, and may be arranged in a horizontal or inclined position. The lever or beam *C*, of wood or other suitable material, is moved along bar *B*, and pivoted with its lower end to beam *b* of the barn. The upper end of the lever *C* carries above or below bar *B*, as may be desired, by suitable staple and hook, the tackle-block *D*, having pulley *d* and weighted lever *F*, pivoted to its upper part. A pulley, *d¹*, is applied to beam *b*, or one of the rafters *A*, near the pivoted end of lever *C* on the side off the starting-point of the same, so that its conveying motion may be communicated by the draft-rope *E*. Rope *E* passes over pulley *d¹*, placed at any suitable point convenient for

the horse or other power, over pulleys *d¹* and *d* of the tackle-block *D* to the hay-fork *G*, having riveted above the same a ferrule, *f*, which, in connection with pin or lug *g*, above pulley *d*, stops the load when arrived at the highest point. Weighted lever *F*, having hook *e* at its lower side, locks over ferrule *f*, and suspends the load for the purpose of conveying the same. A rope, *K*, passes through a staple, *h*, at the end of the lever *C*, to the weighted end of lever *F*, being adjusted with the other end at some suitable point, and at such length that the lever *F* will be immediately released from ferrule *f*, and the fork *G* allowed to descend when lever *C* arrives at the starting-point. As long as rope *K* is slack, lever *F* will lock firmly to ferrule *f*, and keep the fork suspended. The fork *G* is also connected with guide-rope *H*, which passes over pulley *d³*, suspended by a pendent arm or strong band-spring, *I*, at about the height of block *D*, from one of the rafters *A*, above the place of arrival of the hay from the farm. By means of rope *H*, which is adjusted at some point by a knot, ring, or other arrangement, to prevent its slipping over pulley *d³*, the fork *G* may be opened to discharge its load above the place of destination, whenever desired, and lever *C* be brought back again to the starting-point.

The operation of the hay-carrier is as follows: Lever *C* is at the starting-point near pulley *d³*, rope *K* being stretched, so that the fork *G* descends to be discharged. Draft-rope *E* is then pulled by the horse, hoisting the load till ferrule *f* strikes pin *g* of the block *D*, compelling lever *C* to follow, and allowing, by the slackening of rope *K*, the weighted lever *F* to lock the load to the tackle-block. Lever *C* moves with the load over guide-bar *B* to the other end of the same, where the hay is discharged by pulling rope *H* and opening the fork. Lever *C* returns then by means of the inclination of bar *B*, or, if horizontal, by pulling rope *H* to the starting-point, where the fork is instantaneously disconnected from the weighted lever *F* by rope *K* to descend and be charged again. The position of pulley *d¹* compels lever *C* to pass rapidly along bar *B*, and admits of the storing of the hay in very short time, and with great facility.

Having thus described my invention, I claim

as new and desire to secure by Letters Patent—

1. The combination of pivoted lever C and guide-bar B, supported by bars *a*, with tackle-block D, rope E, and pulleys *d*, *d*¹, and *d*², for hoisting and conveying the hay, as described.

2. Tackle-block D, having pulley *d*, pin *g*, and weighted lever F, in combination with rope E, having ferrule *f* to lock the load to the block, as set forth.

3. The combination of lever C and weighted

lever F with rope K, to disconnect rope E and fork G at the starting-point, substantially as described.

4. The combination of lever C and fork G with rope H, pendent-arm I, and pulley *d*³ for releasing the load and returning lever to starting-point, as described.

EUGENE B. TANNER.
